FLYING MACHINE

Claude Dornier, Friedrichshafen-on-the-Boden-
see, Germany, assignor of one-half to Dornier-
Metallbauten G. m. b. H., Friedrichshafen-on-
the-Bodensee, Germany

Application March 1, 1934, Serial No. 713,450
In Germany March 3, 1933

5 Claims. (Cl. 244—102)

My invention relates to flying machines and more particularly to the arrangement, in such machines, of the propellers and the supporting means, such as landing and starting gears, floats, etc. in such machines.

It is an object of my invention to provide means whereby the propellers and the supporting means can be arranged in such manner as to improve the stability and the aero-dynamic efficiency of the craft.

In ordinary airplanes for use on land as well as in seaplanes, flying boats, etc. difficulties are frequently encountered in positioning the propellers sufficiently high above the ground or the surface of the water to prevent their tips from hitting the ground or cutting through the water. Moreover in hydroplanes and more especially in flying boats, if, in order to avoid this, the propeller shaft is positioned sufficiently high above the water to prevent the tips of the propeller blades from entering the water, it may happen that the stability of the craft, more especially when the engines are stopped of a sudden, is greatly impaired.

In order to avoid this and other drawbacks, I provide means for lifting the propeller free of the ground or the surface of the water before landing, and I combine therewith means for simultaneously lowering the landing gear, such as a carriage or the floats supporting the craft.

I may lift the propeller either by a parallel displacement of the propeller shaft or by a tilting movement of the shaft and I may lift or tilt the engine along with the shaft. In either case provision is made for simultaneously lowering the landing gear and for lifting same again, when the propeller is lowered on starting.

In the drawings affixed to this specification and forming part thereof several embodiments of my invention are illustrated diagrammatically by way of example.

In the drawings,

Fig. 1 is a side elevation,

Fig. 2 is a plan view of an airplane having its propeller and engine arranged on the fuselage,

Fig. 3 is a front elevation,

Fig. 4 is an elevation of a twin-propeller airplane,

Fig. 5 is a similar view of a modified form,

Fig. 6 is a front elevation,

Fig. 7 a side elevation of a flying boat,

Fig. 8 illustrating a detail on a larger scale, and

Fig. 9 is a side elevation of an alternative form.

Referring to the drawings and first to Figs. 1 and 2, 1 is the fuselage and 2 is a cowl enclosing

the propeller shaft and engine, 3 being the propeller. The cowl 2 is hinged to the top of the fuselage at 4 so as to be tiltable about a horizontal axis, as shown in dotted lines in Fig. 1. 5, 5 are the wheels of the carriage or landing gear, which are mounted on an axle 6, the ends of which are supported by arms 7 rockable about the axis 8. Links 9 connect the arms 7 with slides 10 mounted for displacement in inclined tracks 11. Rods 12 pivoted to points near the bottom of the cowl 2 extend axially through the fuselage, their rear ends being supported by rollers 13. Sprockets 14 and 15 are disposed in the fuselage above and below the tracks 11, respectively, and endless chains 16 running over these sprockets lower the slides 10, fixed to them, in the tracks when the cranks 17 are turned in the direction of the arrow, and lift them, when the cranks are turned the other way. Sheaves 18 mounted coaxially with the top sprockets 14 serve for winding up cables 19 fixed to the rear ends of the rods 12.

When the cables are wound on the sheaves 18, the rods 12 being pulled forward cause the cowl 2 to tilt about its hinge point 4, thereby lifting the propeller free of the ground. At the same time the sprockets 14 causing the chains to shift the slides 10 from their position of rest, shown in dotted lines, into their lowermost positions allow the landing wheels 5 to be lowered into operative position also. Inversely, if on starting the craft the cranks are turned in clockwise direction, the slides 10 are lifted in the tracks, pulling the links 9 and arms 7 along with them so as to swing the wheels back into inoperative position in the fuselage, while the cables being unwound from their sheaves 18 allow the weight of the engine and propeller to force the cowl back into operative position.

In the airplane illustrated in Figs. 3 and 4 the fuselage 20 is supported by the self-supporting wing 21 between two engine cowls 22 hinged to the front edge of the wing at 23. Arms 24 linked at 25 to supports 26 mounted in the fuselage support the axles 27 of the landing wheels 28, which thus are pivoted to the hull. The top ends of struts 29 embracing these axles are guided in horizontal tracks 30. Cables 31 can be wound on sheaves 32 fixed to an axle 33 extending horizontally across the fuselage substantially in the plane of the axes of the propellers 34, when a worm 35 meshing with a wheel 36 on the axle 33 is turned by means of a crank 37. Other gear wheels 37 fixed on the axle to the rear of the

cowls mesh with gear wheels 38 fixed on the hinge pins 23 of the cowls.

In the operation of this device, when the crank is turned in one direction, the worm 34 will 5 rotate the axle 32 and thereby cause the wheels 37 to rotate the wheels 38 and tilt the cowls and propellers as shown in dotted lines. At the same time the cables 39 being released allow the wheels to be lowered. On the crank being turned the 10 other way the cowls and propellers are lowered again into operative position, while the cables, being wound on the sheaves 31, lift the wheel axles and cause the struts 28 to travel along the tracks 29, until they have reached their 15 horizontal positions of rest in which they are locked by pawls 39 acted upon by springs 40 and governed by cables 41.

Fig. 5 illustrates a very simple form of connection between the propellers and the landing gear. 20 Here the struts 42 carrying the wheel axle are fixed on the axle 43 on which is also fixed the engine cowl 44. By turning the crank handle 45 and rotating the worm 46 a worm wheel 47 keyed on the same axle is rotated and the axle turned 25 in one or the other direction, tilting the cowl and propeller upwardly and lowering the landing gear, or vice versa.

Figs. 6 and 7 show the invention as applied to 30 a flying boat. To the self-supporting wing 58 resting on the hull 51 are hinged at 52 the two engine cowls 53. Parallel links 54, 55 pivoted to the cowl at 56 and to the hull at 57, respectively support the floats 58. The forward links 54 are 35 fixed to an axle 59 extending across the hull and wing and carrying a worm wheel 60 actuated by a worm 61 and crank handle 62. A sprocket wheel 63 on the axle 59 is connected with a sprocket wheel 64 on another axle 65 above it, which extends through the hinge points of the cowls, by 40 means of a chain 66.

Sprocket wheels 67 on axle 65 are connected by 45 chains 68 with similar wheels 69 on the stump axles 71 carrying the links 55.

By turning the handle 62 both axles 59 and 65 can be rotated in the same direction, the cowls being tilted upwardly while the links 54, 55 carrying the floats are lowered, and vice versa.

Fig. 9 illustrates a modification of the device 50 shown in Figs. 7 and 8. Here only the lower axle 70 governing the floats is provided, the cowls being acted upon by thrust levers 71 fixed to this axle and acting on the rear faces of the cowls 72 to turn them upwardly about their hinge points 73.

Obviously in all the embodiments here shown 55 and described the axles may as well be turned by motorial force.

I wish it to be understood that I do not desire 60 to be limited to the exact details of construction shown and described, for obvious modifications will occur to a person skilled in the art.

I claim:—

1. In an aeroplane comprising a hull element and wing elements, the combination of at least 65 one propulsion unit mounted upon a pivotal axis directly on one of said elements, the center of mass of said propulsion unit being located ahead of said pivotal axis, with a landing gear pivoted on one of said elements for extension and retraction, mechanism connected at one end to said landing gear and supporting at least a part of the weight thereof, said mechanism at its other end being connected to said propulsion unit at 70 a point displaced from said pivotal axis, and common actuating means for operating said landing 75 gear and simultaneously, and in dependence thereupon, tilting said propulsion unit relative to said hull and said wings, in a sense opposite to that in which the landing gear moves, whereby the weight of the landing gear at least partially balances the weight of the propulsion unit. 5

2. In an aeroplane, the combination according to claim 1, including a member provided on the landing gear and pivoted to the hull, a guide path secured to the hull and a second member slidably arranged in said guide path, and common actuating means for tilting and raising the propulsion unit and simultaneously sliding said second member in said guide path, thereby lowering said landing gear. 10 15

3. In an aeroplane comprising a hull element and wing elements, the combination of at least one propulsion unit mounted upon a pivotal axis directly on one of said elements, the center of mass of said propulsion unit being located ahead 20 of said pivotal axis, with a landing gear pivoted on one of said elements for extension and retraction, mechanism connected at one end to said landing gear and supporting at least a part of the weight thereof, said mechanism at its 25 other end being connected to said propulsion unit at a point displaced from said pivotal axis, and common actuating means for operating said landing gear and simultaneously, and in dependence thereupon, tilting said propulsion unit 30 relative to said hull and said wings, in a sense opposite to that in which the landing gear moves, whereby the weight of the landing gear at least partially balances the weight of the propulsion unit. 35

4. In an aeroplane comprising a hull element and wing elements, the combination of at least 40 one propulsion unit mounted upon a pivotal axis directly on one of said elements, the center of mass of said propulsion unit being located ahead of said pivotal axis, with a landing gear pivoted on one of said elements for extension and retraction, mechanism connected at one end to said landing gear and supporting at least a part of the weight thereof, said mechanism at its other end being connected to said propulsion unit at a point displaced from said pivotal axis, and common actuating means for operating said landing gear and simultaneously, and in dependence thereupon, tilting said propulsion unit relative to said hull and said wings, in a sense opposite to that in which the landing gear moves, whereby the weight of the landing gear at least partially balances the weight of the propulsion unit, said mechanism and said actuating means comprising 45 struts provided on the landing gear and pivoted to said hull, a guide path provided on said hull 50 and another strut supporting said landing gear slidably arranged in said guide path, said actuating means comprising a rotary shaft provided in said hull, a toothed wheel mounted on said shaft, and a second toothed wheel mounted on said pro- 55 60 65 70 75 80 85 90 95 100

75 80 85 90 95 100

pulsion unit in mesh with the first wheel, a sheave mounted on said shaft and a cable connected to said struts and adapted to be wound on said sheave when said shaft is turned, thereby raising 5 the landing gear while the propulsion unit is lowered.

5. In an hydroplane comprising a hull element and wing elements, the combination of at least one propulsion unit mounted upon a pivotal axis 10 directly on one of said elements, the center of mass of said propulsion unit being located ahead of said pivotal axis, with a landing float pivoted on one of said elements for extension and retraction, mechanism connected at one end to 15 said landing float and supporting at least a part of the weight thereof, said mechanism at its other end being connected to said propulsion unit at a point displaced from said pivotal axis, and common actuating means for operating said

landing float and simultaneously, and in dependence thereupon, tilting said propulsion unit relative to said hull and said wings, in a sense opposite to that in which the landing float moves, whereby the weight of the landing float at least 5 partially balances the weight of the propulsion unit, said mechanism and said actuating means comprising a rotary shaft mounted in said hull, a plurality of arms connected with and actuated by said shaft, said arms carrying said landing 10 float, a sprocket mounted on said shaft, a second rotary shaft mounted in said hull and adapted to have said propulsion unit tiltably mounted thereon, a second sprocket mounted on said second shaft and means for connecting said first 15 with said second sprocket for correlating the rotary movements of said shafts.

CLAUDE DORNIER.
